SIGNAL GENERATING SYSTEM

Harold M. Lewis, Great Neck, N. Y., assignor to
Hazeltine Corporation, a corporation of Delaware

Application May 27, 1937, Serial No. 145,024

2 Claims. (Cl. 178—7.2)

This invention relates to cathode-ray tube television transmitting systems and, more particularly, to an improved method of, and means for, generating signals in such systems.

In accordance with present television practice, a cathode-ray signal-generating tube is employed at the transmitter, the cathode-ray being deflected to scan, in a series of parallel lines, a photosensitive target upon which an image of the scene to be transmitted is projected. For this purpose, the ray is ordinarily deflected horizontally at a relatively high frequency and vertically at a relatively low frequency, the horizontal scanning frequency determining the number of lines per second and the vertical scanning frequency determining the number of frames per second. During each line deflection or trace, the electrostatic potentials of the successive elements of the target, which depend upon the light values at corresponding elements of the scene, are modified by the cathode ray and video-frequency voltages are thereby developed which are representative of these varying light values in the successive elemental areas of the scene. The cathode ray is preferably cut off or blocked out during the line and frame retrace periods so as not to affect the screen. Despite the fact that the ray is cut off during the retrace periods, however, undesirable electrical impulses are developed which, if included as a part of the transmitted signal, seriously impair the reproduction thereof at a receiver. Such impulses are occasioned by various causes inherent in the operation of conventional cathode-ray tube signal-generating apparatus, some of which are not fully understood.

A so-called background-illumination signal is also developed at the transmitter and comprises a unidirectional voltage proportional to the average background illumination of the scene to be transmitted. When the signal is passed through alternating current amplifiers, the unidirectional voltage is, of course, lost. It is essential, therefore, in transmitting systems of the character described, that means be provided whereby the undesired impulses developed during the retrace scanning periods may be suppressed from the signal and the several signal components to be transmitted may be so combined that the resultant modulation signal includes a background-illumination component which may be utilized at a receiver to develop a unidirectional control voltage representative of the average background illumination of the transmitted scene.

Heretofore various systems have been devised in attempts to accomplish the essential require-

ments mentioned above. For various reasons, however, such systems have not proved entirely satisfactory. For example, in these systems of the prior art, it has been found extremely difficult completely to suppress the undesired retrace period impulses and to obtain a sharp cutoff of that part of the signal representative of the "blacker than black" level, whereby the signal will correspond to black during all retrace periods.

10 It is an object of the present invention, therefore, to provide a cathode-ray tube signal-generating system of the character described, whereby there may be developed an undistorted signal substantially free from undesired impulses occurring during the retrace scanning periods and which includes a background-illumination modulation-signal component.

15 In accordance with the present invention, there is provided in a television transmitting system, a cathode-ray tube signal-generating system comprising means including a scanning system for effecting traces and retraces of the ray on the target of the tube for developing video-signal voltages, means for developing pedestal-signal voltages during retrace-scanning periods, and means for developing a separate aperiodic bias voltage having an amplitude varying solely in accordance with background illumination. A vacuum-tube amplifier is provided which includes 20 a plurality of control electrodes and an output circuit, together with means for applying the video-signal voltages to one of the electrodes, means for applying the pedestal signals to one of the electrodes to reduce the transconductance 25 of the tube substantially to zero during periods corresponding to the retrace-scanning periods, and means for applying the developed background-illumination voltage as a bias to the first one of the control electrodes to adjust the zero 30 axis of the wave applied to the amplifier. By such an arrangement, there is developed in the output circuit of the vacuum-tube amplifier a composite signal including the video signal and the background-illumination voltages.

35 40 45 For a better understanding of the invention, together with other and further objects thereof, reference is had to the following description taken in connection with the accompanying drawings, and its scope will be pointed out in the appended 50 claims.

In the accompanying drawings, Fig. 1 is a circuit diagram, partially schematic, of a television-transmitting system including a cathode-ray tube signal-generating system embodying the present invention and Fig. 2 is a group of curves repre-

senting certain operating characteristics of the system of Fig. 1 to aid in the understanding of the invention.

Referring now more particularly to Fig. 1 of the drawings, the television-transmitting system there illustrated comprises a cathode-ray signal-generating tube and camera device of conventional design, indicated generally at 10, and including a signal-generating tube 11 having the usual electron gun, photosensitive target, and scanning elements for effecting traces and retraces of the cathode ray on the target of the tube for developing video-frequency voltages, as indicated. For developing scanning currents for the signal-generating tube, a line-scanning saw-tooth generator 12 and a frame-scanning saw-tooth generator 13 are provided, their output circuits being connected to the scanning elements of the cathode-ray tube 11, as shown. In order to provide pedestal impulses or pedestal-signal voltages for suppressing undesirable signal impulses during the retrace scanning periods, ensuring the proper form of the signal to be transmitted in accordance with the present invention, as further described hereinafter, and for blocking out the cathode ray during the retrace periods, there is provided a pedestal impulse generator 14 having its output circuit connected to the control grid of the signal-generating tube 11 by a suitable lead 15. For developing synchronizing impulses for the signal to be transmitted, a synchronizing impulse generator 17 is provided. The form of combined line- and frame-synchronizing impulses developed by the generator 17 is controlled by voltage from generator 14 supplied to generator 17 via a suitable connection 19. For the purpose of synchronizing the generators 12, 13, 14, and 17, there is provided a timing impulse generator 20, preferably stabilized by means of a connection 21 to a suitable source of periodic voltage, as, for example, to power mains or to the synchronizing voltage source of a motion picture mechanism, where such is employed. The output circuit of the generator 20 is connected to the several other generators, as shown.

For the purpose of providing a separate aperiodic bias voltage having an amplitude varying solely in accordance with background-illumination, there is provided a conventional generator 22 comprising a photoelectric tube 23 having its output circuit connected to the input circuit of a direct current amplifier 24, as shown, the output circuit of the amplifier including a resistor 25 across which the background-illumination control voltage is developed.

Connected in cascade to the output circuit of the signal-generating tube and camera device 10, in the order named, are a video-frequency amplifier 28, a vacuum-tube mixing amplifier 29 including a plurality of control electrodes and an output circuit, a modulation amplifier 30, a modulator 31 which is also coupled to an oscillator 32, as shown, a power amplifier 33, and an antenna system 34, 35, all according to conventional practice. The output circuit of the generator 22 is coupled to the first or control grid of amplifier 29, thereby to utilize the unidirectional control bias developed by generator 22 to adjust the zero axis of the video-signal wave applied to amplifier 29. Synchronizing impulses are also applied to modulation amplifier 30 from generator 17 in accordance with conventional practice. Operating voltages for the tubes 11, 23, 24, and 29 are supplied from batteries, as indicated, or any other suitable sources.

Neglecting for the moment the details of arrangement and operation of the amplifier 29 and the parts of the system associated therewith in accordance with the present invention, the system just described comprises the elements of a television-transmitting system of conventional design and the various parts thereof illustrated schematically being of any well-known construction, a detailed description of the general system and its operation is unnecessary herein. Briefly, however, the image of a scene to be transmitted is focused on the target of the tube 11 in which a cathode ray or beam is developed, focused, and accelerated toward the target. Scanning or deflecting currents developed by the generators 12 and 13 are applied to the scanning coils of the generating tube 11 to provide magnetic fields which serve to deflect the cathode ray horizontally and vertically, thereby to scan successive series of parallel lines, or frames, on the target. The deflecting currents and, hence, the magnetic fields are of well-known saw-tooth wave form providing a relatively slow linear trace and rapid retrace. The number of lines per frame are determined by the relative frame and line frequencies. Pedestal impulses developed by the generator 14 are applied to a control electrode of the tube 11 to suppress or block out the beam during the retrace portions of the scanning cycles and are applied to the amplifier 29 in a manner and for a purpose presently to be described.

Synchronizing impulses developed in the generator 17 are applied to the amplifier 30, while timing impulses developed in the generator 20, stabilized from the power line connection 21, are applied to the generators 12, 13, 14, and 17 to lock these generators in synchronism.

The photosensitive elements of the target being electrically affected to an extent depending upon the varying values of light at the corresponding incremental areas of the image focused thereon, as the cathode ray passes over the target, a voltage of correspondingly varying amplitude is developed in the output circuit of the signal-generating tube 11 and applied to the amplifier 28. The average background illumination of the scene causes the photocell 23 of the generator 22 to develop in its output circuit a negative-bias voltage proportional to this average illumination and this voltage is applied to the control electrode of the direct current amplifier 24, thereby to develop across the resistor 25 a unidirectional voltage component which increases positively in proportion to the background illumination. The video-frequency voltages in the output circuit of the amplifier 28 and the background-illumination voltage developed across the resistor 25 are applied to the amplifier 29. These voltages are combined and amplified in the amplifier 29 and translated to the amplifier 30, wherein they are further amplified and mixed with the synchronizing impulses applied from the generator 17. The modulation voltages are then supplied to the modulator 31, wherein they are impressed on the carrier wave generated by the oscillator 32 and the resultant modulated-carrier signal is delivered to the power amplifier 33 for amplification and thereupon impressed upon the antenna system 34, 35 to be broadcast.

Referring now more particularly to the parts of the system embodying the present invention, the amplifier 29, in the preferred embodiment of the invention, comprises a pentode vacuum tube having the usual cathode, anode, control grid, screen, and suppressor. The control grid-cathode

circuit of the tube 29 is connected to the output circuit of the amplifier 28 by way of a suitable coupling condenser 36 and leak resistor 37, while a filter resistor 39 and inductance 40 are included in the anode circuit of this tube. The anode circuit is coupled to the input circuit of the video-frequency amplifier 30 by means of a suitable coupling condenser 41. The background-illumination voltage lead 27 from the output circuit of the generator 22 includes a suitable time constant resistor 42 and by-pass condenser 43 and is connected to the resistor 37 for applying the unidirectional voltage to the control grid of the tube 29. Pedestal impulses are supplied by a lead 16 from the generator 14 and a suitable coupling condenser 44 to the suppressor of the tube 29 to reduce the conductance of tube 29 substantially to zero during periods corresponding to retrace-scanning periods. Thus, the video-frequency voltages, background-illumination voltage, and pedestal-impulse voltage are all applied simultaneously to the amplifier 29 to be combined therein and thereby develop in the output circuit of amplifier 29 a composite signal including the video-signal and background-illumination voltages.

The operation of the system in accordance with the present invention may best be explained by reference to the curves of Fig. 2. Here, the several curves illustrate the wave forms of signals developed at different points in the system. Only a few line-frequency cycles are shown, the broken lines indicating the omitted impulses. The curves W, G, and B represent the video-frequency voltages developed by the cathode-ray tube 11 and amplified by and appearing in the output circuit of the amplifier 28 for a perfectly white background having a vertical black bar; for a grey background having two adjacent vertical bars, one white and one black; for a black background having a vertical white bar, respectively, each line including a sudden change from positive to negative to represent a sudden change from white to black and/or vice versa. At the end of each line period there is a negative impulse, as indicated at N, occurring during the block-out of the cathode ray during the retrace scanning period. There is also shown, during the retrace intervals, a positive voltage surge, as indicated at S. The impulses N and S are, of course, the undesirable impulse surges which must be removed from the signal. The signal at this point of the system does not include the background-illumination unidirectional voltage component.

Curve A illustrates the grid-voltage plate current characteristic of the tube 29 which, it will be noted, is typical of a tube of the linear, sharp cutoff type. Since both the video-frequency and the background-illumination voltages are applied to the control grid of this tube, the combined voltage appearing thereon is of the form illustrated by the curves W₁, G₁, and B₁. More particularly, the grid of the tube 29 is initially biased so that, with no background bias voltage applied thereto, it operates approximately at cutoff, as indicated by curves B and B₁. The unidirectional background bias voltage, being applied positively and increasing in accordance with increases in the average background illumination of the scene, adjusts the point of operation or the position of the alternating current axis of the video-frequency voltages with respect to the curve A accordingly. Hence, for a black background subject, as represented by the video-frequency voltages B₁, with no background bias volt-

age applied, the point of operation or bias for the tube 29 is indicated at E_b. For the grey and white subjects, the background bias voltage is increased accordingly and operation is at the points E_g and E_w, respectively. Curves P represent the pedestal impulses developed by the generator 14 and applied to the suppressor of the amplifier tube 29. The amplitude of these impulses is not critical when so applied, it being only necessary that it is sufficient completely to cut off the plate current of the tube during the retrace intervals. In a tube in which the suppressor grid has a substantial control, the wave form of the pedestal should, however, be more perfect and should be very flat during the trace portion of the cycle in order that no shading of the lines will be produced thereby.

With the video-frequency, background-control, and pedestal voltages thus applied to the control electrodes of the amplifier tube 29, the plate current of this tube is of a wave form such as represented by the curves W₂, G₂, and B₂. It will be appreciated that, when this signal is impressed upon a succeeding stage through an alternating current coupling, the unidirectional background voltage component is lost. The expression "alternating and direct current amplifier stage," as employed herein and in the appended claims, is intended to denote any amplifier arrangement wherein both the unidirectional and alternating voltage components are transmitted, which arrangement may, of course, include any number of amplifier tubes coupled for both unidirectional and periodic voltages. The signal, as represented by W₂, G₂, and B₂, therefore, is impressed upon the amplifier 30 which may include any desired number of stages. The synchronizing signal impulses, indicated at I, are also applied from the generator 17 to a suitable stage of the amplifier 30 so that these impulses have the same polarity as the pedestal impulses and video impulses representing black. The final modulation voltage developed by the system and appearing in the output circuit of the amplifier 30, therefore, is of the form represented by the curves W₃, G₃, and B₃ and this voltage is utilized to modulate the carrier developed by oscillator 32, as mentioned above.

Due to the translation of the signal through the alternating current coupling, such as condenser 41, the unidirectional voltage component is, of course, lost. However, a background-illumination control component is still included in the signal. That is, the variation in the peak values of the combined pedestal and synchronizing impulses with respect to the axis of the modulation wave is representative of the background-illumination variations and may be utilized at a receiver to provide a unidirectional voltage corresponding to the voltage developed by the generator 22, to provide background-illumination control.

While the suppressor of the amplifier 29 has been found a highly satisfactory point for the application of the pedestal voltages, it will be clear that these voltages may be applied to various other electrodes, such as the control grid or the plate of this amplifier, by suitably modified circuit arrangements. Moreover, if desired, multi-grid tubes of different types may be substituted for the amplifier 29 to provide separate control electrodes for the video-frequency, background-illumination, and pedestal voltages or, if desired, all of these voltages may be applied to a single control electrode of a suitable tube, all such

modified arrangements being well within the understanding of those skilled in the art following the teachings above set forth.

It will thus be seen that the present invention provides an efficient and relatively simple system wherein an undistorted signal is developed which is substantially free from undesired impulses during the retrace scanning periods and which includes a background-illumination modulation signal component.

It will be clear that the operation of the system during the frame retrace interval, when the pedestal voltage is negative during the time required to scan a plurality of lines, is similar to that during line retrace intervals excepting that the form of the undesired impulses are somewhat different. The wave forms during these periods have not been illustrated in the interest of brevity.

While there has been described what is at present considered to be the preferred embodiment of this invention, it will be obvious to those skilled in the art that various changes and modifications may be made therein without departing from the invention, and it is, therefore, aimed in the appended claims to cover all such changes and modifications as fall within the true spirit and scope of the invention.

What is claimed is:

1. In a television-transmitting system, a cathode-ray tube signal-generating system comprising means including a scanning system for effecting traces and retraces of the ray on the target of the tube for developing video-signal voltages, means for developing pedestal-signal voltages during retrace scanning periods, means for developing a separate aperiodic bias voltage having an amplitude varying solely in accordance with background-illumination, a vacuum-tube ampli-

- fier comprising a plurality of control electrodes and an output circuit, means for applying said video-signal voltages to one of said electrodes, means for applying said pedestal signals to one of said electrodes to reduce the conductance of said tube substantially to zero during periods corresponding to said retrace scanning periods, and means for applying said background-illumination voltage as a bias to said first one of said 5 control electrodes to adjust the zero axis of the wave applied to said amplifier, thereby to develop in said output circuit a composite signal including said video-signal and background-illumination voltages.
- 10 2. In a television-transmitting system, a cathode-ray tube signal-generating system comprising means including a scanning system for effecting traces and retraces of the ray on the target means for developing pedestal-signal voltages 15 during retrace scanning periods, means for developing a separate aperiodic bias voltage varying solely in accordance with background-illumination, a vacuum-tube amplifier having an output circuit and comprising a plurality of control 20 electrodes including a control grid and a suppressor grid, means for applying said video-signal voltages to said control grid, means for applying said pedestal-signal voltages to said suppressor grid to reduce the conductance of said 25 tube substantially to zero during periods corresponding to said retrace scanning periods, and means for applying said background-illumination voltage as a bias to said control grid to adjust the zero axis of the wave applied to said 30 amplifier, thereby to develop in said output circuit a composite signal including said video-signal and background-illumination voltages.
